(57) CLAIM

The ornamental design for a photographic mount, as shown and described.

DESCRIPTION

FIG. 1 is a perspective view of the photographic mount showing the new design.

FIG. 2 is a right side elevational view thereof.

FIG. 3 is a left side elevational view thereof.

FIG. 4 is a top plan view thereof.

FIG. 5 is a bottom plan view thereof.

FIG. 6 is a front view thereof; and,

FIG. 7 is a back view thereof.

The broken lines illustrate portions of the photographic mount that form no part of claimed design.
